BOOTH FOR VENDING MACHINES DISPENSING COMESTIBLES AND OTHER PRODUCTS

Sidney Silverman and Betti O. Silverman, both of 372 Darrell Road, Hillsborough, Calif.

Filed May 28, 1962, Ser. No. 70,293

Term of patent 14 years

(Cl. D13—1)

Fig. 1.

Fig. 2.

Fig. 3.

Fig. 4.

FIG. 1 is a front elevational view of a booth for vending comestibles and other products, showing our new design.

FIG. 2 is a top plan thereof.

FIG. 3 is an end elevational view thereof.

FIG. 4 is a side elevational view thereof.

The undisclosed end opposite that shown in FIG. 3 is substantially the same in appearance as the end shown in FIG. 3.

We claim:

The ornamental design for a booth for vending machines dispensing comestibles and other products, substantially as shown and described.
